US012431343B2

(12) **United States Patent**
Jarrell et al.

(10) **Patent No.:** US 12,431,343 B2
(45) **Date of Patent:** Sep. 30, 2025

(54) **INDUCTIVE DETECTOR WITH
INTEGRATED AMPLIFIER**

(71) Applicant: **Waters Technologies Corporation**,
Milford, MA (US)

(72) Inventors: **Joseph A. Jarrell**, Newton Highlands,
MA (US); **Patrick Brophy**, Newton
Highlands, MA (US); **Alistair J.
Schofield**, Oldham (GB)

(73) Assignee: **Waters Technologies Corporation**,
Milford, MA (US)

(*) Notice: Subject to any disclaimer, the term of this
patent is extended or adjusted under 35
U.S.C. 154(b) by 377 days.

(21) Appl. No.: **18/066,067**

(22) Filed: **Dec. 14, 2022**

(65) **Prior Publication Data**

US 2023/0187193 A1 Jun. 15, 2023

Related U.S. Application Data

(60) Provisional application No. 63/289,951, filed on Dec.
15, 2021.

(51) **Int. Cl.**

(57)

ABSTRACT

An image charge detection assembly for a mass spectrometer comprising an image charge detector that is housed within an electrically conductive shielding enclosure, and a preamplifier, wherein at least an input stage of the preamplifier, which is electrically connected to the detector, is housed with the detector within the enclosure.

INDUCTIVE DETECTOR WITH
INTEGRATED AMPLIFIERCROSS-REFERENCE TO RELATED
APPLICATIONS

This application claims priority to and benefit of U.S. Provisional Patent Application No. 63/289,951, filed Dec. 15, 2021. The entire disclosure of which is hereby incorporated by reference.

TECHNICAL FIELD

The present disclosure relates generally to the field of inductive detectors, and more particularly to an inductive detector comprising an integrated amplifier.

BACKGROUND

An ion or charged particle passing through a conductive cylinder produces an image charge on the tube by electrostatic induction. The voltage on the tube is proportional to the charge on the particle but inversely proportional to the capacity of the system. This voltage can be amplified, digitized, and analyzed such that modern detection systems can detect tens to hundreds of elementary charges in a single pass.

The noise in these systems limits the amplitude of the signal that can be observed—or more specifically the signal-to-noise ratio limits the signal that can be observed.

Numerous approaches exist for improving the noise characteristics of these systems. Ions can be repetitiously measured using multi-electrode devices or by using electrostatic ion traps in what is essentially a signal averaging approach utilizing fast Fourier transforms or correlation analysis. Background noise can also be reduced by cooling the detection electronics. Careful trap design considerations can reduce the capacitance of the pickup tube, which improves the voltage observed, produced per charge.

The pickup tube must be physically connected to the input stage of the amplifier. Several approaches have been implemented including the use of conductive rods and thin wires. Prior art arrangements have placed a JFET (junction-gate field-effect transistor) and feedback components inside a metal tube supporting the trap body; utilized an electrostatic ion trap where the amplifier is also placed outside the body of the trap; or designs utilizing printed circuit boards have used secondary connections in the form of wires to interface with amplifier electronics. In all of these implementations, the pickup tube (or electrode) exists as a component independent of the detector circuit. Moreover, the pickup tube is placed inside its own shielded housing through which a secondary conductor must be passed. Such a conventional approach is convenient but suffers drawbacks.

The present invention arose in a bid to address some of the shortcomings of the prior art, in particular in a bid to minimize stray capacitance and parasitics, as experienced with the prior art.

SUMMARY

According to a first aspect, there is provided an image charge detection assembly for a mass spectrometer comprising an image charge detector, which is housed within an electrically conductive shielding enclosure, and a preamplifier, which is electrically connected to the detector and housed with the detector within the enclosure.

2

By such an arrangement, additional conductors, which would be required to make a connection from the detector to the amplifier input, are eliminated.

According to a further aspect, there is provided an image charge detector for a mass spectrometer comprising a preamplifier directly fabricated onto the charge detector.

According to a yet further aspect, there is provided an image charge detector for a mass spectrometer comprising an input stage of a preamplifier directly coupled to the charge detector.

These and other aspects and features of the present disclosure will be more readily understood when read in conjunction with the accompanying drawings. Moreover, it must be noted that the various features of any of the above statements may be combined without restriction, as will be readily appreciated by those skilled in the art.

BRIEF DESCRIPTION OF THE DRAWINGS

FIG. 1 is schematic sectional view of an image charge detection assembly according to a first embodiment;

FIG. 2 shows a schematic partial sectional view of an image charge detection assembly according to a second embodiment; and

FIG. 3 shows a PCB electrode layout of an image charge detector according to an embodiment.

DETAILED DESCRIPTION

With reference to FIG. 1, there is shown an image charge detection assembly for a mass spectrometer comprising an image charge detector 1 and a preamplifier 2. The preamplifier 2 is electrically connected to the image charge detector 1. The image charge detector 1 and the preamplifier 2 are housed together within an electrically conductive shielding enclosure 3.

The enclosure 3 is not particularly limited in form. It may take any suitable form that provides suitable electrical shielding, as will be readily appreciated by those skilled in the art. The enclosure will be provided within a vacuum chamber (not shown). It preferably provides support to the image charge detector 1.

By the unique placement of the preamplifier 2 within the same shielded enclosure 3 as the image charge detector 1, the requirement for additional conductors (for making a connection from the image charge detector 1 to the amplifier input) is eliminated.

In the present arrangement, the image charge detector 1 comprises a cylindrical pickup tube. It must be noted, however, that it may alternatively comprise an Orbitrap, a Fourier Transform Ion Cyclotron Resonance (FTICR) detection cell, a printed circuit board electrode (as discussed below with reference to FIG. 3), or otherwise.

The preamplifier 2 may comprise a single integrated circuit, a circuit board comprising a plurality of discrete components, a hybrid integrated circuit, or otherwise.

The image charge detector 1 is preferably directly connected to the input stage(s) of the preamplifier 2. The direct connection may be accomplished, for example, by directly fabricating a junction-gate field-effect transistor (JFET), or other suitable high-impedance pre-amplifier, onto a body of the image charge detector 1, or by directly coupling the gate of the JFET (or input stage of an alternatively configured pre-amplifier) to the image charge detector 1. The direct coupling of the input stage may be by soldering.

In the arrangement of FIG. 1, the preamplifier comprises a JFET, which has its gate directly connected to a body of the image charge detector 1, which, as discussed, comprises a cylindrical pickup tube.

The image charge detector 1, whatever its form, is preferably provided with a recess 5 in an outer surface thereof, as shown. In this case, the JFET gate may be directly soldered to the image charge detector in the recess 5. Alternative structures will be possible, as will be readily appreciated by those skilled in the art.

The JFET, or any alternative high-impedance pre-amplifier implemented, can also be directly integrated onto the pickup tube, or alternatively structured image charge device 1, by selecting a suitable electrically insulating, thermally conductive, substrate, such as a sputtered aluminum nitride film. This substrate may first be deposited on the outer surface of the electrically conductive tube when fabricating the JFET onto the outer surface of the pickup tube.

Returning to the structure of FIG. 1, the enclosure 3 is attached to a mounting (vacuum) flange 6 via a support tube 5.

With reference to FIG. 2, there is shown an alternative arrangement to that of FIG. 1. The mounting flange and support tube are omitted from FIG. 2. In this arrangement (although it again need not be limited as such), the image charge detector also comprises a cylindrical pickup tube. A PCB mounting pin of a PCB mounted pre-amplifier is directly soldered to the image charge detector 1 in the recess 5. As will be readily appreciated by those skilled in the art, particularly in light of the discussion herein, this represents one only of a number of possible alternative arrangements.

With reference now to FIG. 3, an alternative form of image charge detector 1 is shown, which may, as with the cylindrical pickup tubes of the arrangements of FIGS. 1 and 2, be located in the enclosure of an image charge detection assembly.

The image charge detector 1 comprises a PCB patterned with electrodes. The electrodes consist of alternating regions that are connected to one of two pre-amplifiers in an alternating fashion. As will be appreciated by those skilled in the art, the electrode configuration may be varied from that shown. The depicted arrangement comprises a 11-stage detector using a single PCB. Alternative arrangements will be possible with more or less stages and/or utilizing a plurality of shapes and/or more or less PCBs. There may, for example, be two PCBs placed in a sandwich arrangement with a space in between.

The image charge detector 1 is again directly connected to the input stage(s) of the preamplifiers 2. Here the preamplifiers are shown to comprise JFETs, which has its gate connected to the electrodes. The pre-amplifiers may be otherwise configured. It is preferable that the pre-amplifiers and any supporting electronics are mounted directly on the PCB.

Any implementation discussed herein will be configured, by appropriate selection of materials, to deal with thermal control and outgassing. Vacuum is an excellent thermal insulator. Hence, temperature control of semiconductor devices in a vacuum system can be challenging because the heat these devices may generate is not easily dissipated by conductive pathways. Additionally, the performance characteristics of semiconductor devices often have a strong temperature dependence. Many common printed circuit board materials generate significant outgassing. Thus in order to improve overall performance, it is preferable that these semiconductor components are assembled on ceramic (e.g. aluminum nitride) printed circuit boards or aluminum

base printed circuit boards such as are sold by Hitech Circuits Co., Limited (<https://hitechcircuits.com/>) or AdTech Ceramics (<http://www.adtechceramics.com/>).

Therefore, the disclosed arrangements are well adapted to attain the ends and advantages mentioned as well as those that are inherent therein. The particular embodiments disclosed above are illustrative only, as the teachings of the present disclosure may be modified and practiced in different but equivalent manners apparent to those skilled in the art having the benefit of the teachings herein. Furthermore, no limitations are intended to the details of construction or design herein shown, other than as described in the claims below. It is therefore evident that the particular illustrative embodiments disclosed above may be altered, combined, or modified and all such variations are considered within the scope of the present disclosure. The systems and methods illustratively disclosed herein may suitably be practiced in the absence of any element that is not specifically disclosed herein and/or any optional element disclosed herein. While compositions and methods are described in terms of "comprising," "containing," or "including" various components or steps, the compositions and methods can also "consist essentially of" or "consist of" the various components and steps. All numbers and ranges disclosed above may vary by some amount. Whenever a numerical range with a lower limit and an upper limit is disclosed, any number and any included range falling within the range is specifically disclosed. In particular, every range of values (of the form, "from about a to about b," or, equivalently, "from approximately a to b," or, equivalently, "from approximately a-b") disclosed herein is to be understood to set forth every number and range encompassed within the broader range of values. Also, the terms in the claims have their plain, ordinary meaning unless otherwise explicitly and clearly defined by the patentee. Moreover, the indefinite articles "a" or "an," as used in the claims, are defined herein to mean one or more than one of the elements that it introduces. If there is any conflict in the usages of a word or term in this specification and one or more patent or other documents that may be incorporated herein by reference, the definitions that are consistent with this specification should be adopted.

As used herein, the phrase "at least one of" preceding a series of items, with the terms "and" or "or" to separate any of the items, modifies the list as a whole, rather than each member of the list (i.e., each item). The phrase "at least one of" allows a meaning that includes at least one of any one of the items, and/or at least one of any combination of the items, and/or at least one of each of the items. By way of example, the phrases "at least one of A, B, and C" or "at least one of A, B, or C" each refer to only A, only B, or only C; any combination of A, B, and C; and/or at least one of each of A, B, and C.

Although various example embodiments have been disclosed, a worker of ordinary skill in this art would recognize that certain modifications would come within the scope of this disclosure. For that reason, the following claims should be studied to determine the scope and content of this disclosure.

The invention claimed is:

1. An image charge detection assembly for a mass spectrometer comprising an image charge detector, which is housed within an electrically conductive shielding enclosure, and a preamplifier, which is electrically connected to the detector and housed with the detector within the enclosure;

wherein an input stage of the preamplifier is directly coupled to the charge detector.

5

2. An image charge detection assembly as claimed in claim 1, wherein the charge detector comprises a cylindrical pickup tube, Orbitrap, Fourier Transform Ion Cyclotron Resonance detection cell, or a printed circuit board electrode.

3. An image charge detection assembly as claimed in claim 1, wherein the preamplifier comprises a single integrated circuit, a circuit board comprising a plurality of discrete components, or a hybrid integrated circuit.

4. An image charge detection assembly as claimed in claim 1, wherein the preamplifier comprises a ceramic or aluminum base printed circuit board.

5. An image charge detection assembly as claimed in claim 1, wherein the preamplifier is directly fabricated onto the charge detector.

6. An image charge detection assembly as claimed in claim 5, wherein an electrically insulating, thermally conductive substrate is deposited on a surface of the charge detector.

7. An image charge detection assembly as claimed in claim 6, wherein the substrate comprises a sputtered aluminum nitride film.

8. An image charge detection assembly as claimed in claim 1, wherein the preamplifier comprises a junction-gate field-effect transistor.

6

9. An image charge detection assembly as claimed in claim 1, wherein the enclosure is attached to a mounting flange via a support tube.

10. An image charge detector as claimed in claim 1, wherein the charge detector comprises a cylindrical pickup tube.

11. An image charge detection assembly as claimed in claim 1, wherein the electrically conductive shielding enclosure is housed within a vacuum chamber.

12. An image charge detector for a mass spectrometer comprising a preamplifier directly fabricated onto the charge detector.

13. An image charge detector as claimed in claim 12, wherein an electrically insulating, thermally conductive substrate is deposited on a surface of the charge detector.

14. An image charge detector as claimed in claim 13, wherein the substrate comprises a sputtered aluminum nitride film.

15. An image charge detector for a mass spectrometer comprising an input stage of a preamplifier directly coupled to the charge detector.

16. An image charge detector as claimed in claim 15, wherein the charge detector comprises a recess in an outer surface thereof with the input stage received by the recess.

17. An image charge detector as claimed in claim 16, wherein the input stage is fixed in the recess with solder.
